(57) **CLAIM**

The ornamental design for a sock, as shown and described.

DESCRIPTION

FIG. 1 is a back perspective view of a sock showing the new design;

FIG. 2 is a front perspective view thereof;

FIG. 3 is a left-side elevation view thereof;

FIG. 4 is a left-side perspective view thereof;

FIG. 5 is a right-side elevation view thereof;

FIG. 6 is a right-side elevation view thereof; and,

FIG. 7 is a top plan view thereof.

The broken lines in the figure views depict portions of the sock that form no part of the claimed design.
